UNITED STATES PATENT OFFICE.

RODERICK G. COLLINS, JR., OF NEW YORK, N. Y.

PNEUMATIC-DESPATCH SYSTEM.

1,102,323.

Specification of Letters Patent.

Patented July 7, 1914.

Application filed March 29, 1913. Serial No. 757,523.

To all whom it may concern:

Be it known that I, RODERICK G. COLLINS, Jr., a citizen of the United States, residing at New York, in the county of New York and State of New York, have invented new and useful Improvements in Pneumatic-Despatch Systems, of which the following is a specification.

This invention relates to improvements 10 in pneumatic despatch apparatus, and has for its object to provide an arrangement by which the carriers may be sent through a tube with greater frequency than is possible in previous systems.

15 The invention has also for its object a novel arrangement and combination of parts to facilitate despatching carriers in both directions through a tube.

20 The invention has also for its object to simplify the construction and control of pneumatic despatch apparatus.

With these objects in view the invention consists in the features hereinafter described and claimed, reference being made to the 25 accompanying drawings, which illustrate the preferred embodiment thereof, and in which:—

Figure 1 is a plan view, illustrating one terminal of a duplex apparatus, omitting 30 circuits. Fig. 2 is a plan view of the terminal of one side of the duplex arrangement shown in Fig. 1, and which may be utilized in itself for despatching carriers in both directions through the associated tube. 35 Fig. 3 is a side elevation of that which is shown in Fig. 2, omitting circuits. Fig. 4 is a longitudinal horizontal sectional view of the parts illustrated in Fig. 2, omitting 40 circuits. Fig. 5 is a vertical sectional view on the line *a*—*b* of Fig. 4. Fig. 6 is a sectional view on the line *c*—*d* of Fig. 4. Fig. 7 is a sectional view on the line *e*—*f* of Fig. 4.

In the said drawings the reference numeral 1 designates a tube stretching between 45 terminals 2, one only of which is shown in the drawing, another, of similar character, existing at the opposite termination of the tube 1. In the further description of the invention the terminal 2 shown in the drawings will first be referred to as a receiving 50 terminal, and then as a despatching terminal. The tube, at the terminal, is fashioned into two-branch-terminal-tubes, 3 and 4,

each constituting a continuation of said tube. Said terminal branches communicate 55 with and discharge the carriers onto one or another of a plural member receiving table, 3^a, 4^a, which table-members when the apparatus is of duplex organization lead to the corresponding branches 3^b and 4^b of the terminal 2^a of the tube 1^a. When duplex the terminal 2 may be considered a receiving terminal, and that 2^a a despatching terminal of the apparatus. The advantage of the plural-member termination of the tube 1 and 60 the associated plural-member table as thus far described, is that the carriers may be received, handled, and despatched with greater rapidity, in a practical way, than heretofore—for example, assuming, as is often the 65 case, that after a carrier has been delivered at the terminal of the tube 1, about ten seconds' time is essential for an operative to open up the carrier, remove the contents thereof, and pass it on to a co-employee to 70 be loaded for return despatch, and an equal time for the latter to load, close and despatch the carrier. Hence it is apparent that for continuous receipt and despatch of carriers, the latter should not be sent through 75 the tube 1 at intervals of less than ten seconds, unless there be provision, as in accordance with this invention, for a plural-branch tube-terminal and associated plural-member receiving-table. With such provision, however, the carriers may be sent 80 through the tube 1 at intervals of say five seconds if provision be made for sending the same alternately through the two branches of the terminal, and thus alternately onto the members of the plural-member receiving-table.

To enable this mode of operation to be accomplished I have provided the following 85 novel arrangement: At the juncture of the tube 1 and plural-branch continuations thereof is a pivoted combined-switch-and-air-gate 5, the free edge of which points toward the tubular conduit 1, and is operable to open either terminal-branch for the reception of a carrier from the tube 1, and, coincidently, close the other. The said combined-switch-and-gate moves in what may be conveniently termed a branch box 6, the 90 walls of which that co-operate with the longitudinal edges of the combined-switch-and-

gate being flat so that there may be air-tight contact of the gate therewith, as shown in Fig. 5 of the drawing. This switch-gate is automatically operated to open the branch tubes alternately for communication with the tube 1, and preferably in the manner and by the means shown, in which a walking beam 7 is carried by the pivot of the gate, exteriorly of the branch-box, and has operative connection at its opposite ends with the cores 8 of solenoids 9, such operative connection being, preferably, as shown, a pin and slot connection 10, which will admit of oscillatory movement of the walking beam, and rectilinear movement of the solenoid cores. The solenoid-fields are in circuit, for example, as shown, with a suitable source of electricity, shown conventionally as a dynamo 11, and included in the circuit of each solenoid is an electrical make-and-break switch 12 (see Fig. 5). Combined with each switch is a lever 13, disposed in the path of travel of and to be actuated by the carriers as they pass through the branch tube terminals after having passed the combined switch-and-gate, so that, assuming a carrier has passed into the right hand terminal tube 4, (Fig. 4) contact of the carrier with the switch-lever establishes the circuit of the appropriate solenoid, and, through its core, the walking beam is oscillated, and the combined switch and gate thrown to its opposite position, opening the branch tube 3 to receive the next following carrier, which, in its turn, operating upon the switch-lever appropriated to that branch, moves the combined switch-and-gate to again establish communication between the branch 4 and the tube 1 for the reception of the next following carrier; and so on throughout the operation of receiving carriers, which go alternately into the two branches of the terminal. Near the exit end of each terminal-branch of the tube 1 is a rotary valve 3^c and 4^c, which are normally closed so that the carriers, acting as pistons, come to air-cushion-rest in the tubular branches without shock. Taking one carrier C for illustration, at just about the time it comes to rest in branch 3 (as in Fig. 4) the car operates the switch lever 13 to cause the shifting of the combined air-gate-and-switch, as hereinbefore described, and, at the same time, the associated solenoid 14 (which is in circuit with the switch 13, and a suitable source of electricity) is energized, causing movement of its core 15; and to this core is connected a crank-arm 17 carried by a journal of said valve. This means operates to open the valve to permit passage of the carrier onto the appropriate member of the plural-member table. The ejection of the car may be conveniently accomplished by a blast of air entering the branch tube

behind the carrier as shown at 18. This blast of air may conveniently be supplied from any suitable air compressor 19, and is admitted automatically at the appropriate time in any suitable way, for example as shown in Fig. 2 in which a valve 20 in the blast-conduit has connection 21 with the crank 17 of valve 3^c, and is opened and closed synchronously with the latter. As the carrier emerges from the branch-tube it engages and operates a switch lever 22 to break the circuit 12 through the medium of connection 12^a to close a circuit that includes the solenoid 16 whereby said solenoid is energized, and, operating upon the core 15, closes the valve through the medium of the crank arm, (and the air-blast at 18 is simultaneously cut off) so that the said valve is in operative position to permit the described operation with respect to a subsequent carrier. Before another car goes into branch 3, however, the carrier next following that just referred to will pass into the other branch terminal-tube 4, and the operation hereinbefore set forth be repeated in that tube, including the shifting of the combined switch-and-air-gate, so that the next subsequent carrier will, in its turn, pass into the branch-tube 3.

When the apparatus is constituted as a duplex system, such as illustrated in Fig. 1 of the drawing, the carriers pass alternately onto the members of the plural-member table, where, in small space, ample opportunity is offered for workmen to open up the carriers, remove the contents, reload and send the carriers out through the terminal 2^a, it being understood that when so organized one side of the apparatus will likely be continuously used as a receiving terminal, and the other as a despatching station. In 105 despatching, and this will be clearly understood upon reference to the Fig. 4 of the drawing which has been used in illustration of the operation of receiving carriers, it is essential that the valves 3^c and 4^c of the 110 branch-tubes 3^b and 4^b be opened to admit the passage of the carriers, and, preferably, and as organized, this is accomplished by manual operation of a switch-lever 23 (shown diagrammatically in the drawings 115 and which in practice will be located, one for each branch, in any convenient place for manipulation by a workman) which energizes the coil 14 associated with the hereinbefore mentioned core 15 to establish electrical circuit (independent of that made by the switches 22) through said coil, energize it, and cause said core, through the medium of the crank arm, to open said valve so that a carrier may enter the branch-tube, and then, under the influence of suction from the opposite (not shown) station, be drawn through the branch tube into and through

the appropriate transmitting tube to the said opposite station. In its transit through the said tube the electrical connections remain undisturbed, since the switch levers 13 and 22 are moved in a direction which does not establish either of the electrical circuits. In despatching, the several successive carriers may, if desired, be sent through the same branch tube into the transmitting tube, but if conditions require that the carriers be sent alternately through the members of both branches illustrated, that may be accomplished, as each branch is provided with duplicate mechanism; and to enable this mode of operation to be carried out provision is made for manual shifting of the combined switch-and-air-gate. As shown this arrangement consists of a rod 24 connected with the walking beam 7, and having a handle 25 pivoted at its end to a bracket 26 supported conveniently at the end of the tube, so that the position of the combined air-gate-and-switch may be controlled at the will of the operator, to permit sending of the carriers through the branch-tubes alternately, or, at will, have the successive carriers pass through but one branch tube. The switch levers 23 are arranged to also establish circuits through the coils 16 associated with the cores 15, and when energized either of the coils influence its core to close, through the medium of the crank arm, the valve 3^e or 4^e, after the sending operation through either of the branches 3 or 4 is finished, and thus the valves in said branches are ready to perform their part as elements of a receiving terminal. The circuits through coils 16 established by switch levers 23 are, of course, independent of those established by the carriers acting on the switches 13.

As hereinbefore stated, where the apparatus is not organized as a duplex system, one side of the apparatus illustrated in Fig. 1 (to wit, that shown in Figs. 2 and 4) may be used as both a receiving and sending terminal, as will be obvious from the foregoing description.

The apparatus is adapted for use as a suction apparatus, or as a blast apparatus.

The reference numeral 27 (Fig. 2) designates a conduit which places the fan 28 in communication with the tube 1. When the system is organized as a blast system the terminal shown in Fig. 2 will, of course, be a sending terminal, and the conduit 27 will be in communication with the blast side of the fan so as to drive the carriers through the tube 1 by blast. When the system is organized as a suction system the terminal shown in Fig. 1 must be considered as a receiving terminal, and the conduit 27 as in communication with the suction side of the power fan, so as by suction to draw the carrier from

the sending to this receiving station. My 65 invention has nothing to do with the details of this alternative organization, and the same is mentioned only incidentally to make it appear that the matter of my invention may be embodied in either a suction or blast 70 organization. When operated by suction the momentum of the carrier by the time it reaches the point of communication of the conduit 27 with the tube 1 will no doubt be sufficient to carry the car past the air gate, 75 and operate the trip to close the gate behind it. When operated upon the blast plan the air gate will be moved to close the branch which is to receive the carrier, and the carrier will be manually pushed into such 80 branch tube past the valve 3^e or 4^e, and predominant compressed air from a suitable source, shown conventionally at 29, may be introduced at 31 behind the car to propel it until it is taken care of by the blast from the 85 fan 28, and, of course, the operator will shift the gate 5 to permit passage of the carrier into the transmitting tube 1.

The construction and arrangement of parts, mode of operation, and advantages 90 thereof are sufficiently set forth in the foregoing description to be obvious to those skilled in the art.

Having thus described my invention what I claim is:—

1. A pneumatic-despatch apparatus, comprising a transmitting tube provided at its terminal with plural-member terminal-branches, a plural-member table communicating with said branches, and automatic 100 means in the path of movement of the carriers for directing said carriers alternately into said terminal branches.

2. A pneumatic despatch apparatus comprising a transmitting-tube provided at its 105 terminal with plural-member terminal-branches, a plural-member table communicating with said branches, a switch located at the juncture of said tube and branches, and means located in the path of movement 110 of the carriers for operating said switch to direct said carriers into said terminal branches alternately.

3. A pneumatic despatch apparatus comprising a transmitting-tube provided at its 115 terminal with plural-member terminal-branches, a plural-member table communicating with said branches, a combined-switch-and-air-gate located at the juncture 120 of the transmitting-tube and its terminal branches, and means, part of which are arranged in the path of travel of carriers through said branches and connected to said combined-switch-and-gate, to automatically shift the position of the latter to alternately 125 open and close communication of said terminal branches with the transmitting-tube.

4. A pneumatic-despatch apparatus com-

prising a transmitting tube provided at its terminals with plural-member terminal-branches, a plural-member receiving-table communicating with said branches, a combined-switch-and-air-gate located at the juncture of the transmitting tube and the terminal branches, trips arranged in the path of travel of carriers through said branches, and means associated with said trips and combined-switch-and-gate to automatically shift the latter to alternately open and close communication of said terminal branches with the transmitting tube.

5. A pneumatic-despatch apparatus comprising a transmitting tube provided at its terminal with plural-member terminal-branches, a plural-member receiving-table communicating with said branches, a blower, a connection therefrom to the transmitting tube for transporting the carriers through said transmitting tube, trips arranged in the path of travel of the carriers through said branches, a combined-switch-and-air-gate located at the juncture of the transmitting tube and the terminal-branches and intermediate said pneumatic transporting means and trips, and means associated with said trips and combined-switch-and-air-gate to automatically shift the latter to alternately open and close communication of said terminal-branches with the transmitting tube.

6. A pneumatic-despatch apparatus comprising a transmitting tube having a plural-member terminal, the branches of which are adapted to be placed in communication with said transmitting tube, a pivoted combined-switch-and-air-gate located at the juncture of said tube and its branches and adapted to open and close communication of said branches with said transmitting tube, trips located in the path of travel of carriers through said terminal-branches, and means associated with said trips and said combined-switch-and-gate for shifting the position of the latter.

7. A pneumatic-despatch apparatus comprising a transmitting tube provided at its terminal with plural-member terminal-branches, a combined-switch-and-air-gate located at the juncture of said tube and branches and adapted to be shifted to place either of said branches in communication with the transmitting tube, trips arranged in the path of travel of carriers through said branches, normally closed valves in said branches, and means co-operatively associated with said trips, combined-switch-and-gate and valve whereby said switch-and-gate is automatically shifted to close either branch-terminal after the passage of a carrier thereinto, and the valve in such branch is opened to permit passage of the carrier out of the terminal-branch.

8. A pneumatic-despatch apparatus com-

prising a transmitting tube provided at its terminal with plural-member terminal-branches, a combined-switch-and-air-gate located at the juncture of said tube and branches and adapted to be shifted to place either of said branches in communication with the transmitting tube, trips arranged in the path of travel of carriers through said branches, normally closed valves in said branches, means co-operatively associated with said trips, combined-switch-and-gate and valve whereby said switch-and-gate is automatically shifted to close either branch-terminal after the passage of a carrier thereinto, and the valve in such branch is opened to permit the passage of the carrier out of the terminal-branch, and means connected to and operable from said valves for admitting an air blast for ejecting a carrier from the branch-tubes.

9. In a pneumatic-despatch apparatus comprising a transmitting tube provided at its terminal with plural-member terminal-branches, a combined-switch-and-air-gate located at the juncture of said tube and branches and adapted to be shifted to place either of said branches in communication with the transmitting tube, trips arranged in the path of travel of carriers through said branches, normally closed valves in said branches, means co-operatively associated with said trips, combined-switch-and-gate and valve whereby said switch-and-gate is automatically shifted to close either branch-terminal after the passage of a carrier thereinto, and the valve in such branch is opened to permit the passage of the carrier out of the terminal-branch, means connected to and operable from said valves for admitting an air blast for ejecting a carrier from either branch-tube, trips at the exit end of the terminal-branches in the path of movement of the carriers therefrom, and means associated with said trips and said terminal-branch-valves for closing the latter.

10. A pneumatic-despatch apparatus comprising a transmitting tube provided with a plural-branch-terminal, a plural-member table communicating with said branches, a combined-switch-and-air-gate at the juncture of said tube and branches, means actuated by the passage of a carrier through either of said branches for shifting the position of said switch-and-gate, and auxiliary means connected to said gate and operable at will for shifting the position thereof.

11. A pneumatic-despatch apparatus comprising a transmitting tube having a plural-member terminal, the branches of which are adapted to be placed in communication with said transmitting tube, a pivoted combined-switch-and-air-gate located at the juncture of said tube and its branches and

adapted to open and close communication of said branches with said transmitting tube, trips located in the path of travel of carriers through said terminal-branches, and electrically operated means actuated by said trips to shift the position of said combined-switch-and-gate.

In testimony whereof I have hereunto set my hand in presence of two subscribing witnesses.
